(57) **CLAIM**

An ornamental design for an electrical enclosure, as shown and described.

DESCRIPTION

FIG. 1 is a front top right perspective view showing our new design for an electrical enclosure.

FIG. 2 is a front top left perspective view.

FIG. 3 is a front view.

FIG. 4 is a top view.

FIG. 5 is a bottom view.

FIG. 6 is a left side view.

FIG. 7 is a right side view; and,

FIG. 8 is a back view.

The broken lines in the drawings depict portions of the electrical enclosure that form no part of the claimed design.
